UNITED STATES PATENT OFFICE

EDWARD F. BORRO, OF TOTOWA BOROUGH, NEW JERSEY, ASSIGNOR TO MACK MOLDING CO., OF WAYNE, NEW JERSEY, A CORPORATION OF NEW JERSEY

CAP FOR CONTAINERS

Application filed May 12, 1931. Serial No. 536,896.

This invention relates to caps or closures for containers, such as are usually provided for holding powders, such as talcum powders, etc., for the retail trade, and more particularly to caps for such containers which are molded of suitable compositions as phenolic condensation products, etc. Containers such as described are usually formed with a cylindrical neck closed at its outer end by a wall having discharge openings therein. The cap is made of a diameter to fit about the cylindrical neck but due to inaccuracies in manufacturing, the diameters of the necks vary slightly but sufficient to cause cracking of the usual molded caps designed for the designed diameter of the neck. It is an object of this invention to provide an improved cap for containers of the type described which can be fitted to containers, the necks of which vary in diameter slightly, and it is also an object of this invention to provide an improved molded cap for containers which can be fitted to containers without cracking.

In the drawings—

Figure 1 is a view in elevation of a container provided with a cap constructed in accordance with this invention, part of the cap and container neck being broken away to show the relation thereof more closely;

Figure 2 is a view similar to Figure 1 but taken substantially at right angles thereto; and

Figure 3 is a section on line 3—3 of Figure 1.

In the drawings a cap 1 is constructed in accordance with this invention is shown in connection with a container 2 having a neck 4 which is usually closed at its outer end by a perforated wall 6. Owing to the unavoidable inaccuracies of manufacture the diameters of the necks 4 of different containers differ slightly from the designed diameter. Where molded caps of the designed diameter are applied to such containers the irregularities in the diameters of the container necks cause some of the caps to be cracked as they are forced onto the container neck owing to the lack of elasticity of the material forming the cap which does not permit

of a sufficient stretching of the cap. To overcome this objection the cap 1 is molded with its wall or flange 8 inclosing an oval or elliptical opening with its shorter axis 9 of the length of the designed diameter of the container neck it is to fit and its longer axis slightly larger. As thus shaped the cap is found to possess sufficient elasticity to permit of it being applied to container necks which vary within fairly wide tolerances without danger of cracking.

In applying the cap to the container neck the cap is distorted changing the shape of the opening slightly but the compositions have sufficient elasticity to permit of this distortion when, as shown in Figure 3, there is a small clearance left between the cap and the container neck on the longer axis of the cap and the cap flange is not subjected to great tension. The distortion, while slight, is sufficient to permit the application of the cap without danger of breaking and the elasticity of the material of which the cap is made is sufficient to bind the cap in position.

The engaging surfaces of both the container neck and cap are even or plain, without engaging recesses or projections and the cap is retained in position solely by the frictional engagement of the contacting surfaces. The engagement between the cap and the container is such that the cap is retained in position on the container under ordinary handling but is readily removed or applied.

I claim—

1. The combination with a container having a discharge spout with an even cylindrical outer surface of a cap therefore formed of a phenolic condensation compound and having a flange with a continuous even inner surface forming an oval opening when disengaged from the spout, said cap being retained on said spout by the frictional engagement of said surfaces.

2. The combination with a container having a discharge spout with an even cylindrical outer surface of a cap therefore formed of a phenolic condensation compound and having a flange with a continuous even inner

- surface forming an oval opening when disengaged from the spout and distorted by said spout to retain said cap on said spout by frictional engagement of said surfaces when applied thereto.
3. The combination with a container having a discharge spout with a continuous even cylindrical outer surface of a cap of a phenolic condensation compound therefor having a flange with an even inner surface forming an oval opening when disengaged from the spout and distorted by said spout to retain said cap on said spout by frictional engagement of said surfaces when applied thereto.
- 10 4. In a cap of a molded phenolic condensation compound for a container having a discharge spout with an even cylindrical outer surface, a flange having a continuous even inner surface and forming an oval opening to receive said discharge spout, the shorter axis of the oval opening of the cap being substantially the length of the diameter of the discharge spout.
- 15 5. In a cap of a phenolic condensation compound for a container having a discharge spout with an even cylindrical outer surface, a flange having a continuous even inner surface and forming an oval opening, said opening being distorted when the cap is in position on the discharge spout and said surfaces retaining said cap in position by frictional engagement.
- 20 6. In a cap of a phenolic condensation compound for a container having a discharge spout with an even cylindrical outer surface, a flange having a continuous even inner surface and forming an oval opening to receive said discharge spout.
- 25 In testimony whereof I have signed my name to this specification.

EDWARD F. BORRO.
